UNITED STATES PATENT OFFICE.

BENJAMIN C. TILGHMAN, JR., OF PHILADELPHIA, PENNSYLVANIA.

SAND-BLAST MACHINERY.

SPECIFICATION forming part of Letters Patent No. 727,030, dated May 5, 1903.

Application filed July 8, 1902. Serial No. 114,765. (No model.)

To all whom it may concern:

Be it known that I, BENJAMIN C. TILGHMAN, Jr., a citizen of the United States of America, residing in the city and county of Philadelphia, in the State of Pennsylvania, have invented certain new and useful Improvements in Sand-Blast Machinery, of which the following is a true and exact description, reference being had to the accompanying drawings, which form a part thereof.

My invention relates to sand-blast machinery, and has for its object to simplify the construction of such machinery and at the same time to facilitate the even flow of sand to the combining-chamber.

A special object of my invention is to dispense with the use of air-locks and of air-tight sand-admission valves, such as are commonly employed in pressure sand-blast apparatus, and I have also generally in view the avoidance by the use of novel devices and combinations of difficulties heretofore met with in the use of such machines.

The leading feature of my invention consists in the use, in combination with a combining-chamber in which a current of air under pressure mixes with and from which it sweeps the sand to a point of use, of a feed-conduit having its top, in effect, open to the atmosphere that is not exposed to the pressure existing in the combining-chamber, said conduit being adapted to contain a column of sand of a weight greater than the pressure of air in the combining-chamber and being connected to supply sand to the orifice or orifices through which it flows into the combining-chamber and having its lower end exposed to the pressure of the air in the combining-chamber or connected parts. By preference, and this is in practice of great importance, the lower end of the feed-conduit should have an opening or openings for the admission of the high-pressure air separate and distinct from the feed-orifice by which the sand is supplied to the combining-chamber, and for the best results the construction should be such that the air-pressure at the feed-orifice is practically balanced. These conditions are conveniently secured by causing the feed-conduit to deliver its sand into a hopper-like chamber, from which in turn the feed-orifice leads, the upper part of the hopper being

open to the air-pressure, as is the lower part of the feed-conduit.

Another important feature of my invention consists in providing, in connection with the feed-conduit, means for heating it and the sand within it so as to maintain the sand at such a temperature as will prevent the condensation of moisture within it. This is highly important, because there is a constant current of air passing upward through the feed-conduit and diminishing in pressure as it rises, with the natural result of tending to deposit moisture, and such deposited moisture will of course soon prevent the natural and proper flow of the sand.

Another feature of my invention is designed to overcome difficulties met with in sand-blast apparatus owing to the blocking up of the feed-orifice leading to the combining-chamber. This is a not infrequent occurrence and is due to many causes, and I obviate this difficulty by providing in or close to the orifice where stoppages occur a slot and in said slot a sliding plate having one or more orifices which can be made to register with the feed-orifice and which by moving the slide can be shifted to a position in which they dump any material contained in them. By preference I make this slide with abutments which strike against the feed-hopper at the extremes of its movement, which facilitates the discharge of material contained in the orifice and also the reestablishing of a flow of sand from the hopper.

Another feature of my invention, designed especially to obviate stoppages in the feed-conduit due to the tendency of the sand to arch, is the provision of a rod extending through the feed-conduit in the line of flow of sand and movable therein, by means of which this arching of the sand can be prevented or overcome. The rod may be moved either longitudinally or by rotation.

Other features of my improvements will be best understood as described in connection with the drawings, in which they are illustrated, and in which drawings—

Figure 1 is a sectional elevation of a sand-blast apparatus constructed in accordance with my invention and embodying my improvements in what I believe to be its best commercial form. Fig. 2 is a cross-sectional

view on the line 2 2 of Fig. 1; Fig. 3, a similar view showing the slide in the alternative position to that shown in Fig. 2. Fig. 4 is a similar view illustrating a modification 5 in the slide construction. Figs. 5, 6, 7, and 8 are sectional elevations showing various modifications embodying my improvements, and Fig. 9 is a view showing a modification within my invention.

10 A indicates the combining-chamber—that is to say, the place where the air mixes with the sand and begins the work of carrying it along through the conduit to the point of delivery. The combining-chambers, as shown 15 in Figs. 1, 5, and 8, are substantially alike. In Fig. 6 the combining-chamber (indicated at a) is the outlet of a hopper-shaped chamber E², through which the sand falls, and in Fig. 7 the combining-chamber (indicated at 20 a') is of still a different construction.

A', Fig. 1, indicates the mouth of the tube making up the combining-chamber and opening into the pressure-chamber C, into which leads the conduit E, coming from the 25 pressing fan or machine, (indicated at E'). B is the hopper by which the combining-chamber is fed with sand through a feed-orifice, (indicated at B'). The top of the hopper is open, as indicated at B², and it is 30 closed in the pressure-chamber C, from which the air enters the combining-chamber.

In the construction indicated in Fig. 5 the pressure-chamber is omitted and the connection C' made from the supply-pipe E, which 35 in this case connects directly with a combining-chamber to the upper part of the hopper, (here indicated at B³), the top of which in this construction is closed, and in Fig. 8 the equivalent of the hopper is found in the contracted 40 end b of the feed-conduit H, b² indicating an opening into the feed-conduit above and to the side of the nozzle through which the sand enters the combining-chamber A. In Fig. 6 the feed-conduit H connects with a base-casting 45 B⁴, having a hopper-shaped bottom terminating in a feed-orifice, the conduit H having one or more openings b⁵ formed in its lower end for the entry of air, and the escape of sand from such opening being prevented by 50 shelves, such as B⁵, thrown out below said openings.

In Fig. 7 a hopper (indicated at B⁵) is shown; but it is sufficiently similar to the hopper indicated in Fig. 1 to need no special description except to note that the sand issues from the hopper through an annular series of openings, (indicated at b'), the delivery-pipe passing out through the hopper through the center of the series of feed-orifices.

55 D indicates the conduit through which the air under pressure and sand pass to the delivery-nozzle D'. In Figs. 1, 5, 6, and 8 the conduit is represented as a hose with a contracted delivery-nozzle, and in Fig. 7 the conduit (marked d) is shown as an upright metal pipe having a delivery-nozzle at its upper end. F (best shown in Figs. 2, 3, and 4) is a regu-

lating-gate for adjusting the sand-delivery nozzle. In Figs. 2 and 3 it is operated by means of a hand-lever F', the adjustable screw F² being provided to regulate the size of the orifice, the lever being moved freely in the other direction to cut off the supply of sand. In Fig. 4 the adjustment and all movements of the gate or valve F is made through 75 a nut (indicated at F³) working on the threaded end of the rod attached to the gate.

B⁶ (shown in Figs. 2, 3, and 4) is a slot formed, as shown, immediately above the orifice and immediately above the adjusting-valve F, and G is a slide moving through this slot and provided with a transverse opening, (indicated at G'), which can be made to register with the feed-orifice, as shown in Fig. 2, or shifted with the slide to one side, as shown 85 in Fig. 3.

G² is a rod by which the slide is moved, and G³ and G⁴ abutments formed on the slide, which strike against the edges of the hopper at the extremes of its movement, not only 90 limiting the movement of the slide, but giving abrupt jar both to the slide and to the hopper. In the construction shown in Fig. 4 the slide is provided with two openings, (indicated at G' and g'), which are alternately 95 moved into registration with the sand-orifice as the sand is shifted from one side to the other.

H is the feed-conduit, which, as shown in Figs. 1, 5, 6, 7, and 8, is open at the top and, as shown, provided with a hopper H', the lower end of the conduit opening either into the combining-chamber, as indicated in Fig. 8, or into some connection having the same pressure as the pressure-chamber C, as in Figs. 1, 6, and 7, or into the closed hopper B³, as shown in Fig. 5. In Fig. 9 the upper end of the conduit H connects by a spout L⁵ with the hopper L⁴, in which the pressure would be somewhat less than atmospheric, 100 and theoretically a somewhat heavier column of sand in conduit H would be necessary to overcome the pressure at the base of the column. The constructions are, however, practically equivalent, and my invention includes 105 in its scope any modification in which the weight of the sand column is utilized to overcome the air-pressure at its base, as distinguished from the old constructions, in which the air under pressure is admitted to the top 110 of the feed-box to balance the pressures acting on the sand therein. The height of the feed-conduit must in all cases be such as will enable it to be kept charged with a column of sand the weight of which above the point 115 where the conduit is exposed to the pressure fluid will be greater than the pressure of the fluid, so that the pressure will not raise the sand in the conduit, but only result in the escape of a certain limited amount of compressed air through the mass of sand.

I, Figs. 1 and 7, indicates a rod extending through the feed-conduit in the line of movement of the sand and which can be moved

either vertically, as by means of a lever I' , (see Fig. 1,) or rotatable, as by means of a hand-wheel and gear, as shown at I^2 in Fig. 7.

5 J is a steam-jacket surrounding the feed-conduit H, J' indicating a steam-supply entering it, and J² a drip-pipe leading from its bottom.

K is a grating forming the floor of the chamber or place where the sand-blasting is done 10 and which permits the sand to escape through it into a hopper-shaped chamber K', having a spout K², which leads to a combining-chamber L, and a suction-pipe K³, which also leads to the combining-chamber L.

15 L' indicates the upwardly-extending tube of a pneumatic elevator, opening into a chamber L⁴ at top, from which chamber leads a conduit L⁵, connected with the suction-fan L⁶.

L⁷ is a baffle-plate placed immediately above 20 the top L² of the tube L'.

L⁸ is a spout leading from the bottom of the chamber L⁴ into the hopper H' of the feed-conduit H, L⁹ indicating a gate for this spout.

25 M indicates the object to which the sand-blast is being applied.

In the operation of the apparatus indicated in Fig. 1 the blower or compressor E' forces air under pressure through the pipe E into the pressure-chamber C, from which it passes 30 through the opening A' into the tube making up the combining-chamber A and through it and the tube D and nozzle D'. The sand is charged into the feed-conduit H, filling the hopper B below it and filling the feed-conduit 35 to a height which, as before stated, will secure a column of sand above the lower end of the conduit, which will exert a pressure per square inch at that point greater than the pressure of the pressure fluid. The sand 40 passes downward through the opening B' to the slide G and through the feed-orifice in the slide into the combining-chamber and is swept along with the air to the nozzle, fresh sand coming into the hopper from the feed-conduit to make up for the amount delivered 45 through the feed-orifice. A certain amount of the pressure fluid will of course escape upward through the sand in the feed-conduit, diminishing in pressure as it rises, and con-

50sequently tending to deposit moisture and to diminish the temperature of the sand column. This tendency, however, is counteracted by the heating of the sand column, which is most conveniently effected by a steam-jacket J, but obviously can be effected in other well-known ways. In fact, any device which will keep the sand in the feed-conduit at proper temperature is the full equivalent for the steam-jacket. The tendency of the sand to arch in the feed-conduit, 55 and thus arrest or check the flow of sand, is counteracted by the rod I, which may be either moved vertically, as by the lever I' in Fig. 1, or rotatable by the hand-wheel I² in Fig. 7, in either case effectually preventing or overcoming the tendency to arch. The tendency of the feed to choke is overcome by

means of the slide G, which when a total or partial choking is observed is moved by the rod G² cutting out the sand or other material contained in the opening G' and permitting it to drop outside of the combining-chamber—as, for instance, would be the case when the slide is shifted from the position shown in Fig. 2 to that shown in Fig. 3. The sand 75 from the nozzle which falls upon the grated floor K passes through it to the hopper K' and thence through the spout K² to the combining-chamber L. Air at the same time enters the bottom of the combining-chamber, 80 preferably sucked from the sand-blast chamber and, as shown, through the bottom of the chamber K', through the pipe K³ and its connection K⁴, and the air-current, carrying the sand with it, passes upward through the 85 pneumatic lift-pipe L', issuing from its top I² against the baffle-plate L⁷, and falling into the chamber L⁴ into the chamber L⁷ and suction-fan L⁸, and the sand collecting in the chamber L⁴ is permitted to issue through the 90 spout L⁵ into the hopper H', supplying the feed-conduit H, the apparatus being thus rendered automatic and self-supplying.

The operation of the modification shown in Figs. 5, 6, and 7 is sufficiently obvious to need 95 no further description; but as to the modification of Fig. 8 I will note that the platform O is supplied surrounding the contracted nozzle b of the feed-conduit H to form an arresting-floor for the sand which issues through the lateral orifices, (indicated at b²), and which orifices are supplied for the entrance of air to the bottom of the feed-conduit and to avoid an upward draft of air through the feed-orifice for the sand.

Having now described my invention, what I claim as new, and desire to secure by Letters Patent, is—

1. In a sand-blast machine having a combining-chamber into which the sand and pressure fluid flow and mix and from which the mixed fluid and sand are led for use, said chamber having a passage for the entrance of sand, the combination therewith of a sand-feed conduit arranged to deliver sand to the 111 said passage and in free communication with said chamber at its base, said feed-conduit being at the top free from the pressure in the combining-chamber and extending above its base connection with said chamber to a height 112 which will give a sand-pressure at the chamber connection in excess of the fluid-pressure at the same point, and a restricted sand-blast nozzle through which the mixed sand and fluid issues from the chamber and by means 113 of which the pressure in the chamber is maintained at a considerable degree above atmospheric pressure.

2. In a sand-blast machine having a combining-chamber into which the sand and pressure fluid flow and mix and from which the mixed fluid and sand are led for use, said chamber having a passage for the entrance of sand, the combination therewith of a sand-

- feed conduit arranged to deliver sand to the said passage and in free communication with said chamber at its base, said feed-conduit being at the top free from the pressure in the combining-chamber and extending above its base connection with said chamber to a height which will give a sand-pressure at the chamber connection in excess of the fluid-pressure at the same point, and means for heating the sand as it descends through the sand-feed conduit to prevent the condensation of moisture therein.
3. In a sand-blast machine, a feed-conduit for sand adapted to contain a solid column and delivering its sand to a combining-chamber in combination with a rod extending through the feed-conduit and means for moving said rod to prevent the jamming of the sand.
- 20 4. In a sand-blast machine having a chamber into which the sand and pressure fluid flow and mix and from which the mixed fluid and sand are led for use, said chamber having a passage for the entrance of sand, the combination therewith of a sand-feed conduit arranged to deliver sand to the said passage and in free communication with said chamber at its base said feed-conduit being at the top free from the pressure in the combining-chamber and extending above its base connection with the chamber to a height which will give a sand-pressure at the chamber connection in excess of the fluid-pressure at the same point, and a rod extending through the central part of the feed-conduit and movable therein.
5. In a sand-blast machine having a chamber into which the sand and pressure fluid flow and mix and from which the mixed fluid and sand are led for use, said chamber having a passage for the entrance of sand, the combination therewith of a sand-feed conduit arranged to deliver sand to the said passage and in free communication with said chamber at its base, said feed-conduit being at the top free from the pressure in the combining-chamber and extending above its base connection with the chamber to a height which will give a sand-pressure at the chamber connection in excess of the fluid-pressure at the same point, a rod extending through the central part of the feed-conduit and movable therein and means for heating the sand in said feed-conduit to prevent condensation of moisture therein.
6. In a sand-blast machine having a chamber into which the sand and pressure fluid flow and mix and from which the mixed fluid and sand are led for use, said chamber having a passage for the entrance of sand, the combination therewith of a sand-feed conduit arranged to deliver sand to the said opening and having a base connection with the chamber other than and at a higher level than the feed-opening into the chamber, said feed-conduit being at the top free from the pressure in the combining-chamber and extending above its base connection with the chamber to a height which will give a sand-pressure at the chamber-opening in excess of the fluid-pressure at the same point and a heating-jacket surrounding the feed-conduit.
7. In a sand-blast machine having a chamber into which the sand and pressure fluid flow and mix and from which the mixed fluid and sand are led for use, the combination therewith of a sand-hopper having a feed-orifice through which the sand flows to the combining-chamber and a connection from its upper end to the combining-chamber for the passage of the pressure fluid, a sand-feed conduit opening into the hopper and at the top free from the pressure in the combining-chamber, said conduit extending above its opening into the hopper to a distance which will give a sand-pressure in excess of the fluid-pressure at its said opening.
8. In a sand-blast machine having a chamber into which the sand and pressure fluid flow and mix and from which the mixed fluid and sand are led for use, said chamber having a passage for the entrance of sand, the combination therewith of a sand-feed conduit arranged to deliver sand to the said opening and having a base connection with the chamber other than and at a higher level than the feed-opening into the chamber, said feed-conduit being at the top free from the pressure in the combining-chamber and extending above its base connection with the chamber to a height which will give a sand-pressure at the chamber-opening in excess of the fluid-pressure at the same point and means for heating the sand in the feed-conduit to prevent condensation of moisture therein.
9. In a sand-blast machine having a chamber into which the sand and pressure fluid flow and mix and from which the mixed fluid and sand are led for use, said chamber having a passage for the entrance of sand, the combination therewith of a sand-feed conduit arranged to deliver sand to the said opening and having a base connection with the chamber other than and at a higher level than the feed-opening into the chamber, said feed-conduit being at the top free from the pressure in the combining-chamber and extending above its base connection with the chamber to a height which will give a sand-pressure at the chamber-opening in excess of the fluid-pressure at the same point, and a heating-jacket surrounding the feed-conduit.
10. In a sand-blast machine the combination of a combining-chamber for pressure fluid and sand, said chamber having a passage for the entrance of sand, a restricted sand-blast nozzle through which the mixed sand and fluid issue and by means of which the pressure in the combining-chamber is maintained a considerable degree above atmospheric pressure, a feed-conduit arranged to supply sand to the feed-passage and of a height sufficient to maintain a sand column having a pressure at its base connection with

the chamber greater than the fluid-pressure thereat, a hopper arranged to receive the sand-blast after it is used, an elevated receptacle for the sand arranged to supply sand to the feed-conduit and mechanism acting to elevate the sand received in the hopper for used sand and deliver it to said elevated chamber.

11. In a sand-blast machine the combination of a combining-chamber for pressure fluid and sand, said chamber having a passage for the entrance of sand, a restricted sand-blast nozzle through which the mixed sand and fluid issue and by means of which the pressure in the combining-chamber is maintained a considerable degree above atmospheric pressure, a feed-conduit arranged to supply sand to the feed-orifice and of a height sufficient to maintain a sand column having a pressure at its base connection with the chamber greater than the fluid-pressure thereat, a hopper arranged to receive the sand-blast after it is used, a pneumatic sand-lift and elevated hopper to receive the sand from said lift and a conduit from said elevated hopper to the top of the sand-feed conduit.

12. In a sand-blast apparatus having a combining-chamber for pressure fluid and sand,

said chamber having a passage for the entrance of sand thereto, the combination therewith of a feed-conduit for supplying sand to said passage, a transverse slot leading across said passage and a slide moving in said slot and having a passage formed therethrough which in one position of the slide coincides with the feed-passage and in another position opens freely outside of said passage.

13. In a sand-blast apparatus having a combining-chamber for pressure fluid and sand, said chamber having a passage for the entrance of sand thereto, the combination therewith of a feed-conduit for supplying sand to said passage, a transverse slot leading across said passage and a slide moving in said slot and having a passage formed therethrough which in one position of the slide coincides with the feed-passage and in another opens freely outside of said passage, said slide having also an abutment or abutments arranged to strike against a portion of the apparatus at the end of one or both movements.
